(57) **CLAIM**

The ornamental design for a charging unit for two battery packs, as shown and described.

DESCRIPTION

FIG. 1 is a top perspective view of a charging unit for two battery packs showing my new design;

FIG. 2 is a top view of a charging unit for two battery packs according to FIG. 1;

FIG. 3 is a bottom view of a charging unit for two battery packs according to FIG. 1;

FIG. 4 is a right side view of a charging unit for two battery packs according to FIG. 1;

FIG. 5 is a left side view of a charging unit for two battery packs according to FIG. 1;

FIG. 6 is a front view of a charging unit for two battery packs according to FIG. 1;

FIG. 7 is a rear view of a charging unit for two battery packs according to FIG. 1; and,

FIG. 8 is a bottom perspective view of a charging unit for two battery packs of FIG. 1.
